United States Patent Office

Des. 181,409
Patented Nov. 12, 1957

181,409

AIRCRAFT FLIGHT INSTRUMENT

Edward R. Dayton, Huntington Station, and George H. Kaelin, Jr., Westbury, N. Y., assignors to Sperry Rand Corporation, Great Neck, N. Y., a corporation of Delaware

Application October 28, 1955, Serial No. 38,610

Term of patent 14 years

(Cl. D52—1)

FIG. 1.

FIG. 2.

Fig. 1 is a front elevation view of an aircraft flight instrument showing our new design; and

Fig. 2 is a side elevational view thereof.

The dominant features of our design are those portions of Figs. 1 and 2 shown in solid lines. The lining on the drawing represents contrasting colored areas.

We claim:

The ornamental design for an aircraft flight instrument, as shown and described.
